UNITED STATES PATENT OFFICE.

AUGUSTUS F. HARTER, OF OAK PARK, ILLINOIS, ASSIGNOR TO CRIBBEN & SEXTON COMPANY, OF CHICAGO, ILLINOIS, A CORPORATION OF ILLINOIS.

GAS RANGE.

Application filed March 14, 1923. Serial No. 624,963.

To all whom it may concern:

Be it known that I, AUGUSTUS F. HARTER, a citizen of the United States, residing at Oak Park, in the county of Cook and State 5 of Illinois, have invented a new and useful Improvement in Gas Ranges, of which the following is a specification.

This invention relates particularly to a gas-stove, or gas-range, of the type which 10 is provided at one side with an oven or tier of ovens, and opposite the oven, with what is known as a cooking top, that is, a top which is equipped with grids, or open-work plates for supporting the cooking utensils, 15 the usual series of burners being disposed beneath these grids.

The primary object is to provide certain improved features of construction in a gas-range of this type. An important feature 20 is that of an improved construction whereby the walls, which partially surround the open space above the cooking top, are made more sanitary. In this construction, use is made of a rear vertical splasher-plate and a side 25 vertical splasher-plate, these splasher plates being enamelled and applied in an improved manner, whereby the structure is rendered more sanitary and danger of injury to the enamel on the splasher plates is obviated.

30 Further objects of the invention will appear from the detailed description herein-after given.

The invention is illustrated in its preferred embodiment in the accompanying 35 drawings, in which—

Figure 1 represents a front elevational view of the improved gas-range; Fig. 2, a broken front elevational view, showing certain details; Fig. 3, a broken vertical section taken in a vertical plane perpendicular to the front of the range, as indicated at line 3—3 of Fig. 2; Fig. 4, a broken horizontal sectional view taken as indicated at line 4—4 of Fig. 2; Fig. 5, a broken perspective view of the side splasher-plate employed; Fig. 6, a broken vertical section taken parallel with the front side of the range as indicated at line 6—6 of Fig. 7; Fig. 7, a broken horizontal sectional view 45 taken as indicated at line 7—7 of Fig. 6; Fig. 8, a broken view of a rear splasher-plate; and Fig. 9, a broken section taken as indicated at line 9 of Fig. 7.

The range comprises, in the embodiment 55 illustrated, a broiling oven A, surmounted

by a baking oven A', which preferably are constructed as a single unit; a cooking-top B flanking the tier of ovens; a shelf or ledge B' disposed a suitable distance above the cooking top, there being an intervening 60 open space B² flanking the oven A'; the usual group of burners and burner connections C disposed below the cooking top; a chamber D beneath the cooking top, this chamber being open at its front side and 65 serving to receive cooking utensils temporarily, if desired; a removable drip pan D' in the upper portion of the chamber D and disposed beneath the burners associated with the cooking top; and legs E attached to a 70 perimetral metal band E' which is connected with the base portion of the stove-body.

For the most part, the stove-body is constructed of sheet metal. In the preferred 75 construction of the ovens, there is employed a front cast metal frame plate 1, which is of general angular cross-section, as appears from Figs. 3 and 7. The plate 1, in combination with the oven doors 2 and 3, provides 80 a front for the ovens.

The plate 1, which is in the nature of a perimetral member, comprises the vertical members 1^a, the top-member 1^b, the bottom-member 1^c, and the intermediate cross-member 1^d. These members bound the door openings 4 and 5. The member 1 is cast as an integral member. At the margins of the door openings, the metal of the member 1 is offset inwardly to provide a perimetral 90 recess 1^e, this recess serving to receive a marginal portion, or frame, of the door, so that the door frame is about flush with the front face of the skeleton plate 1, as will be understood from Figs. 3 and 7. 95

The angular skeleton plate 1 is provided with a rearwardly turned flange 1^f, which inclines slightly rearwardly and downwardly to permit the proper draw for the casting. Similarly, the front flanges of the casting may be given a suitable draw downwardly, the purpose being to enable the casting to be removed readily from the mold. The rearwardly extending flange 1^f of the upper member 1^b is provided at its rear 100 edge with a rabbet 1^g, which is adapted to receive the front margin of the outer sheet metal member 6 of the oven-top, as shown in Fig. 3. The downwardly turned flange of the member 1^b is provided on its rear side 110

and its lower edge with lugs 1^b serving to support the front margin of the inner sheet metal top-member 7. An air space 8 is thus provided between the top plates 6 and 7 of 5 the oven, as appears from Fig. 3.

The side wall of the ovens, which is adjacent the cooking top of the range comprises preferably an upper sheet metal plate 9 and a lower sheet metal plate 9^a, as appears from Figs. 6 and 7. The rear edges 10 of these plates are equipped with flanges which are connected by bolts 10, with the rear sheet metal plates 11 and 12 which constitute the rear wall plates of the stove, as 15 appears from Fig. 7. The plate 11 constitutes the rear plate of the ovens, while the plate 12 constitutes the rear plate back of the chambers B² and D. There are provided, however, a rear splasher-plate 13 and a side 20 splasher-plate 14 (Figs. 4, 5 and 6), these splasher plates being suitably enamelled on their exposed surfaces, thus affording sanitary surfaces adjacent the open chamber B² which may be designated, the open cooking 25 chamber.

The cooking top B comprises an angular perimetral member 15 which supports the removable grids 15^a. As shown in Fig. 6, the lower marginal portion of the upper 30 side plate 9 is offset outwardly; thus affording a recess which receives the upper margin of the lower side plate 9^a. The overlapping margins of these two plates are secured between a horizontal angle member 35 16 and the adjacent portion of the member 15, as shown in Fig. 6, the parts being connected by bolts 17. It will be observed that the construction provides a horizontal slot or recess 18 between the member 15 and the 40 plate 9 above the offset lower margin of the plate 9.

The rear splasher-plate 13 fits freely under the shelf B' and against the rear wall plate 12. It is enamelled on its front surface and is provided, as shown in Fig. 7, with a vertical flange 13^a which bears against the plate 9. The splasher plate 14 is enamelled on its outer surface. This plate is provided at its front vertical edge with an 50 offset flange 14^a and is provided at its rear vertical edge with a curved flange 14^b whose free edge abuts against the rear splasher plate 13. The offset front edge flange 14^a engages a vertical slot 19 which, as shown in 55 Fig. 7, is left at the front edge of the plate 9. That is, a small vertical slot is left at the front edge of the plate 9 and the rearwardly turned flange 1^c of the frame member 1; and the offset flange 14^a of the splash- 60 er plate 14 hooks into or engages this narrow vertical slot, while the curved flange 14^b abuts against the adjacent margin of the rear splasher plate 13, the curved flange 13^b affording a vertical quarter-round as will 65 be understood from Fig. 7. As has been

stated, the rear vertical edge of the side plate 9 is bolted to the rear plates 11 and 12, while the lower margin of the plate 9 is bolted to the members 15 and 16. The upper margin of the plate 9 is bolted to a down-turned flange 6^a of the top plate 6 of the oven, the parts being connected by bolts 20, as shown in Fig. 6; and, as already stated, the front edge of the plate 9 is cut away, or stops short of the frame-member 1, leaving 70 the narrow vertical slot 19. The lower edge of the splasher plate 14 fits into the socket which is afforded by the narrow slot or recess 18 between the member 15 and the side plate 9. As has been stated, the offset flange 80 of the splasher plate 14 hooks into the slot 19, while the quarter-round 14^b presses firmly against the rear splasher plate 13, the vertical flange 13^a of the plate 13 being concealed behind the quarter-round. The 85 upper edge of the splasher plate 14 is clampingly held by means of a horizontal strip or cleat 21 which is provided with perforations, which are engaged by the stove-bolts 20.

Thus, it will be understood, that the side 90 splasher-plate 14 serves to hold the adjacent end of the rear splasher-plate 13 in position; and the splasher plate 14 is itself well secured in position without the use of any bolts passing through the splasher-plate. 95 The construction is such as to prevent warping stress being placed upon the splasher-plates in the event of any racking of the stove, as in transportation or while the stove is being set up. This obviates cracking or 100 peeling of the enamel. Moreover, the construction provides smooth joints and avoids cracks or crevices wherein dirt might accumulate.

Within the oven and separated from the 105 side plates 9 and 9^a by a space 22 is a plate 23 which is provided at its front and rear vertical edges with inward offsets or channels 23^a. The channels 23^a have secured thereto horizontal cleats or shelf-supports 24 which support the skeleton shelves 25. At the rear 110 of the oven is an inner plate 26 which is separated from the rear plate 11 by a space 27. The construction of the ovens at their outer side is similar to the construction already described and is not shown in detail. Any suitable burner, or burners, is provided for the oven. The burner 28 is indicated in Figs. 6 and 7, the supply tube for this 115 burner being designated 28^a.

The construction at the base of the stove-body may be any suitable construction. In the illustration given, the lower edge of the side plate 9^a of the oven is secured between a down-turned flange 29 of the bottom plate 29^a of the storage chamber D and an angle member 30, the parts being connected by stove-bolts 31, as shown in Fig. 6. A fillet or spacing strip 32 is interposed, as shown. The lower edge of the inner side plate 23 120

of the oven rests upon the horizontal flange of the angle-iron 30. The upper margin of the inner plate 23 is turned outwardly affording the flange 23^b which serves as a 5 spacing flange. Upon this flange rests the inner top plate 7 of the oven, the plate 7 having an up-turned spacing flange 7^a. The base strip E' is secured to the base portion of the stove-body by means of bolts 33. Be- 10neath the oven A are horizontally disposed angle bars 34 which support the inner plates of the oven.

As has been indicated, the cooking top B is connected at one side with the oven, as 15 shown in Fig. 6. It is connected at its rear side with the rear plate 12 and at its outer end it is supported on vertical angle bars 35 and a sheet metal end plate 35^a.

The shelf B' may be of sheet metal which 20 may be curved at its front edge to provide a suitable bead. One end of the shelf is attached to the upper portion of the oven by suitable means (not shown). The other end is supported by a sheet metal standard 36 25 which constitutes a rudimentary side wall, as shown in Fig. 4. In practice, this side plate varies in width and is given a suitable contour to render the design a pleasing one.

In the illustration given, the cooking top 30 B is provided with a detachable shelf or extension B³. This is demountable in any suitable manner (not shown). Above the plane of the shelf B' and the oven-top is a rear panel or back-guard 37 which may be 35 formed by extending the rear plates of the stove-body upwardly and providing suitable beading or moldings to afford an agreeable design.

The doors 2 and 3 may be of any suitable 40 construction. In the construction shown, each door is provided with a perimetral frame-plate 38 which preferably is of cast metal. This plate is provided at its lower part with lateral extensions 38^a. These ex- 45 tensions have formed integrally therewith pivot members 38^b which are curved and which extend inwardly through slots 39 with which the frame member 1 of the oven is provided at suitable points. The details 50 of the hinge-connections need not be stated in further detail, as they form no part of the present invention. The frame member 38 of the door has secured thereto the sheet metal plates 40 and 41 which are so formed 55 as to provide between them an air space, as shown in Fig. 3. The details need not be further described, as they form no part of the present invention.

The rear splasher plate 13 may be secured 60 in position in any suitable manner. In Fig. 4, the outer end of the plate is shown bearing firmly against the standard-plate 36. The lower edge of the splasher plate 13 fits in a recess 18^a between the perimetral top-member 15 and the rear wall-plate 12 (Fig. 9) in

a manner analogous to the manner in which the side-splasher plate 14 is shown held in Fig. 6. The upper edge of the plate 13 is held by a clamping-strip 13^d (Fig. 6) which is secured to the rear wall-plate 12 by bolts 70 13^c and which corresponds with the clamping-strip 21 for the plate 14. In the illustration given, the oven doors 2 and 3 are equipped at their upper margins with rigidly secured handles 42.

The plate 14 is notched at all four corners, as indicated at 14^a. That is, the flanges are cut away slightly. Both of the plates 13 and 14 are reversible and so will serve as "rights" and "lefts." For this purpose, the 80 plate 13 is notched at its corners, as indicated at 13^a. This enables the lower edge of the plate to enter the recess 18^a (Fig. 9). Thus, the plates are used at the left of the oven in the illustration given; but they may be used 85 at the right of the oven where the cooking-top is located at the right of the oven. The flanges serve to stiffen the plates and prevent buckling, thus protecting the enamel. The quarter-round 14^b fills in one vertical corner 90 at the rear of the cooking space B², and the quarter-round 13^b, formed integrally with the outer end of the plate 13, fills in the other vertical corner. This feature renders it easier to keep the splasher-plates wiped clean 95 and in a sanitary condition.

The foregoing detailed description has been given for clearness of understanding, and no unnecessary limitations should be understood therefrom, but the appended claims 100 should be construed as broadly as permissible in view of the prior art.

What I regard as new, and desire to secure by Letters Patent, is:

1. In a gas-stove, the combination of an 105 oven, a stove-top at one side of said oven, above which and flanking said oven is an open space, said oven having a side wall separating the oven chamber from said open space, a vertical slot being provided at the front vertical edge of said wall, and a splasher-plate having its front vertical edge provided with an offset flange which interlockingly engages said slot.

2. In combination, in a gas-stove, an oven 110 having a front vertical corner member, a rear wall, and a side plate secured at its rear end to said rear wall, and having its front vertical edge separated from said corner member by a narrow vertical space affording a slot, a stove-top extending laterally from said oven, a splasher-plate above said stove-top having an offset front edge flange engaging said slot, and a clip secured to the upper portion of 115 said oven and engaging the upper margin of said splasher-plate.

3. In combination in a gas-stove, an oven 120 having a side plate equipped on its outer side with a horizontal frame-member serving as a grid-support for a stove-top, a horizontal 130

- recess being provided between said frame-member and said side plate and a narrow vertical slot being provided at the front edge of said side-plate, a rear vertical wall back of 5 the open space above said stove-top, a splasher-plate having its lower edge entered in said horizontal recess, having its rear edge engaging said rear wall, and having its front margin offset and affording a flange which 10 engages said vertical slot, and a clip secured to the upper portion of said oven and clampingly engaging the upper margin of said splasher plate.
4. In combination in a gas-stove, an oven 15 having a side plate, said oven being provided at its front vertical corner with a splasher-plate socket, a stove-top extending laterally from said oven, a ledge extending laterally from the upper portion of the oven and separated from said stove-top by an open space, 20 a rear vertical wall back of said space, a rear splasher-plate adjacent said wall, a side splasher plate having its rear edge engaging said rear splasher-plate to hold it in position 25 and having its front edge entered in said socket, and a clip securing said side splasher-plate in position.
5. In combination in a gas-stove, an oven 30 having a front comprising a perimetral frame member and oven doors mounted on said frame member, said oven being provided with suitable rear, top and outer side walls and having an inner side plate secured at its upper edge to the oven-top and secured 35 at its rear edge to the rear wall of the oven, the front edge of said side plate being separated from said perimetral frame member by a space affording a narrow slot, a stove-top extending laterally from said oven, a small 40 horizontal recess being provided between said stove-top and said side plate, a shelf extending laterally from the rear portion of the oven-top, a rear wall back of the open space above said stove-top, a rear splasher- 45 plate interposed between the stove-top and said shelf, and a side splasher-plate having its lower edge entered in said recess and having its front margin offset and engaging said slot and having its rear edge provided 50 with a curved flange engaging the adjacent end portion of the rear splasher-plate.
6. In a gas-stove, an oven comprising a cast-metal skeleton front plate of angular cross-section, said skeleton plate affording a perimetral member having a rearwardly extending flange and an inwardly extending flange, doors mounted on said skeleton plate, sheet metal members secured to and substantially flush with the rearwardly turned flanges of said skeleton plate and affording 60 outer walls for the oven, and inner sheet metal plates separated by spaces from the outer plates and having their front edge portions engaging the inwardly extending flanges of said skeleton plate. 65
7. In combination in a gas-stove, a stove-top having a perimetral grid-supporting plate, an oven having an upper side-plate with an outwardly offset lower margin bearing against the adjacent member of said grid-supporting plate and having a lower side-plate overlapping the offset portion of the upper side plate, an inner horizontal frame member at the joint between said plates, bolts connecting said inner frame 70 member to the adjacent member of said grid-supporting plate, a socket being provided between the grid-supporting plate and the base portion of the upper side plate, a rear sheet metal plate back of the space above 75 said stove-top, a rear splasher-plate above the stove-top adjacent said rear sheet metal plate, a side splasher-plate having its front edge provided with interlocking connections with the front corner portion of the oven 80 and having its rear edge bearing against the rear splasher-plate, and a clip securing said side splasher-plate in position. 85
8. In combination in a gas-range, an oven, a stove-top extending laterally therefrom, a shelf separated from the stove-top by an open space bounded by an oven wall, a back wall and a partial side wall, a pair of mutually engaging enamelled splasher plates adjacent the oven wall and back wall, and clamping 90 clips securing said plates to said oven wall and back wall. 95
9. In combination in a gas-range, an oven, a stove-top extending laterally therefrom, a shelf separated from the top by an open space bounded by an oven wall, a back wall and a rudimentary side wall, enamelled back and side splasher plates, there being integrally formed vertical fillets on said plates filling the vertical corners of said space, and 100 clips clampingly securing the splasher-plates in position. 105

AUGUSTUS F. HARTER.
